SUCTION APPARATUS

Willie Roy, Quebec, Quebec, Canada

Application May 24, 1937, Serial No. 144,333

1 Claim. (Cl. 230—92)

The present invention relates to improvements in suction apparatus particularly adapted for absorbing blood during surgical operations.

An object of the invention is the provision of 5 blood suction apparatus of generally improved design.

Another object of the invention is the provision of suction apparatus of the above character which is constructed so as to permit accurate 10 regulation of the suction action.

A further object of the invention is the provision of suction apparatus of the aforesaid character of the fluid velocity type which may be operated by ordinary water pressure.

15 Still another object of the invention is the provision of a suction apparatus of the above character which is relatively simple in construction and efficient and reliable in operation.

Other objects and advantages of the invention 20 will become apparent as the description progresses.

In the accompanying drawing forming a part of this specification and in which like reference characters are employed to designate corresponding 25 parts throughout the same:—

Figure 1 is a perspective view of the assembled apparatus,

Figure 2 is a vertical longitudinal section 30 through the same, and

Figure 3 is a transverse section taken on the line 3—3 of Figure 2.

Referring to the drawing, wherein for the purpose of illustration is shown a preferred embodiment of the invention, 10 generally designates the 35 body of the apparatus, in the present instance, in the form of a flat, approximately rectangular, metallic block having a through bore 11 formed longitudinally through the centre portion. The major portion of the through bore 11 is integrally screw threaded, while the lower portion, providing an ejection passage, is mainly smooth.

At the intermediate portion of the bore 11, that is, at the lower end of the threaded section, is mounted a removable nozzle 12 embodying an 40 upper enlarged portion threadedly engaging the bore and an elongated axial extension shank 13, of reduced diameter. The nozzle is formed with a central through bore 14, of relatively small diameter, and is provided in the top with a

45 transverse groove 15 to facilitate its threaded connection. In one side of the body block is formed an angular passage 17, having a longitudinal or vertical leg 18 extending to the bottom end of the body and an upper horizontal leg 19 running into the upper threaded section of the

central through bore 11, above the upper inlet end of the nozzle 12. As shown, the top of the through bore 11 is normally closed by a screw plug 20.

In the opposite side of the body block 10 is formed an angular passage 22 embodying a vertical leg 23 extending to the top of the block and having the lower inturned leg running into and communicating with the lower ejection passage forming portion of the central through bore. As illustrated at Figure 2, the angular passage 22 10 runs into the through bore at a point just below the threaded connection of the nozzle and at a point above the bottom outlet end of the nozzle shank.

A discharge pipe 25 is threadedly connected 15 with the lower end of the central bore. A ring 26 is mounted in the upper end of the pipe 25, in the lower portion of the bore, so as to form an annular section of restricted diameter in the ejection passage. An angular pipe 28 is attached 20 to one side of the body by extension through a bore in the upper side portion, in communicative connection with the upper portion of the angular passage 22. A fluid supply pipe 30 is threadedly connected with the lower end of the angular feed passage 17, this pipe being equipped 25 with a control valve 31 for controlling the passage of fluid into the feed passage. A vacuum gauge 33, of any preferred type, is connected with the upper end of the angular passage 22 so as to 30 indicate the vacuum created in this passage. To a bore 35 through the front of the body block 10, in communication with the upper end of the angular passage 22 in the block, is connected the inner end of an air supply fitting 36, in the present example in the form of an angular air connection of the type commonly employed on radiators, equipped with a valve 37 embodying an operating disc 38.

To the outer end of the angular pipe 28 may be 40 connected a flexible tube 40 attached to a liquid drain fitting 41, of the type commonly employed for draining or absorbing blood during surgical operations.

The apparatus operates as follows:

The supply conduit 30 may be connected with the tap of an ordinary city water supply system, so as to operate the apparatus by the customary pressure thereof. By opening the valve 31 the water, under superatmospheric pressure, is conducted through the angular feed passage 17 of the body into the upper portion of the main central bore thereof and is discharged downwardly through the restricted bore 14 of the nozzle. As the water discharges through the lower end of 55

the nozzle at a relatively high velocity, through the lower ejection passage and the restricted section thereof, vacuum is created in this passage and within the angular suction passage 22 so that suction is created in the tube 40 and in the blood absorbing device 41. Upon opening the valve 37 of the air supply fitting, a regulated supply of air may be admitted to the suction passage to selectively vary the vacuum therein. While the vacuum created in the fluid velocity passage may be regulated to some extent by operation of the supply valve 31, much greater accuracy of regulation is attained by the operation of the air valve 37 controlling the inlet of air from the atmosphere into the suction passage. The actual vacuum created in the apparatus may be determined by inspection of the gauge 33 so that the desired suction in the suction line 40 is accurately maintained.

As will be readily apparent, this apparatus provides a compact, relatively simple structure for suction operation in connection with fluids and is especially adapted for drainage and absorption action in surgical operations. It is particularly efficient in view of the ability to very accurately regulate the suction created in the vacuum line.

It is to be understood that the form of my in-

vention herein shown and described is to be taken as a preferred example of the same, and that various changes as to the shape, size and arrangement of parts may be resorted to without departing from the spirit of the invention or the scope of the subjoined claim. 5

Having thus described my invention, I claim:—

A suction apparatus of the character described comprising a body, said body having a passage formed therethrough, means closing said passage at one end, said body having a liquid inlet passage connected perpendicular to said first passage formed therein, said body having an exhaust passage formed therein connected perpendicular to said first passage and below said inlet passage connection, a restricted nozzle removably positioned in said first passage below the connection with said inlet passage, a narrow portion of said nozzle extending past the connection of said exhaust passage to said first passage, an exhaust pipe connected to said exhaust passage by a passage formed in said body, an air inlet valve connected to said exhaust passage by a passage formed in said body, and a vacuum gauge connected to and closing the outer end of said exhaust passage. 15

WILLIE ROY.
